UNITED STATES PATENT OFFICE

162,763

HAT

Elaine Weissberger, Brooklyn, N. Y.

Application January 20, 1950, Serial No. 7,365

Term of patent 3½ years

(Cl. D3—13)

To all whom it may concern:

Be it known that I, Elaine Weissberger, a citizen of the United States, residing at Brooklyn, county of Kings, State of New York, have invented a new, original, and ornamental Design for a Hat, of which the following is a specification, reference being had to the accompanying drawing, forming part thereof.

Fig. 1 is a front elevational view of a hat, showing my new design;

Fig. 2 is a top plan view thereof;

Fig. 3 is a side elevational view;

Fig. 4 is a rear elevational view, and

Fig. 5 is a bottom plan view thereof.

I claim:

The ornamental design for a hat, as shown.
ELAINE WEISSBERGER.
